SET OF CARDS FOR PLAYING A BASEBALL GAME

Raymond Francis Nekuda, Kansas City, Mo.

Application April 16, 1952, Serial No. 19,346

Term of patent 7 years

(Cl. D34—13)

To all whom it may concern:

Be it known that I, Raymond Francis Nekuda, a citizen of the United States, residing at Kansas City, in the county of Jackson and State of Missouri, have invented a new, original, and ornamental Design for a Set of Cards for Playing a Base Ball Game, of which the following is a specification, reference being had to the accompanying drawing, forming part thereof.

Fig. 1 is a face view of a card representative of the 53 cards on one suit of a set of cards for playing a baseball game, showing my new design; and

Fig. 2 is a face view of a card representative of the 26 cards in the other suit thereof.

The backs of all of the cards in the set have a conventional appearance.

I claim:

The ornamental design for a set of cards for playing a base ball game, as shown and described.

RAYMOND FRANCIS NEKUDA.
